UNITED STATES PATENT OFFICE.

GEORGE M. KELLER, OF BALTIMORE, MARYLAND, ASSIGNOR TO THE CROWN CORK AND SEAL COMPANY OF BALTIMORE CITY.

CLOSURE.

1,276,077.

Specification of Letters Patent. Patented Aug. 20, 1918.

Application filed November 11, 1916. Serial No. 130,728.

To all whom it may concern:

Be it known that I, GEORGE M. KELLER, a citizen of the United States, residing at Baltimore city and State of Maryland, have 5 invented certain new and useful Improvements in Closures, fully described and represented in the following specification and the accompanying drawings, forming a part of the same.

10 This invention relates to closures for bottles and the like and particularly to that type of closures known as crown corks.

Such closures ordinarily comprise a skirted shell or cap and a sealing disk of cork 15 or other suitable material. Since the crowns are subjected to more or less handling between manufacture and capping, it is necessary to provide means for holding the sealing disk in place, and for various 20 reasons it is desirable that this retaining means should be positive and sure. For example, in the method ordinarily employed in feeding crowns to a capping head, a mass of crowns is dumped into a hopper in which 25 the crowns are agitated by suitable devices in order that they may be selected by the selecting apparatus. It has been found that sealing disks are oftentimes shaken out of their shells by this more or less violent treatment, and as a result, when such incomplete 30 closure reaches the capping head, either a bottle is broken or an imperfect seal is made.

It is the object of the present invention to provide a closure for bottles in which the sealing disk is firmly and effectively held in place and, further, a closure such that the retention of the disk is attained in a simple and economical manner.

The following specification describes, and 40 the accompanying drawing illustrates a bottle closure constructed in accordance with the invention, it being understood that changes may be made in the form, construction and arrangement of the parts without departing from the invention, the form herein disclosed being a preferred embodiment thereof.

In the drawing—

Figure 1 is a vertical cross-sectional view 50 of a bottle closure embodying the invention; Fig. 2 is a plan view showing the bottom of the closure; and

Fig. 3 is a view similar to Fig. 1, showing the closure on a bottle after capping.

55 Referring to the drawing, a closure of the

crown cork type is illustrated, comprising a metal shell or cap 10, having a depending skirt 11 which is formed with vertical inner corrugations 12 and outer corrugations 13. Within the embrace of the skirt and up 60 against the top of the shell is placed a flat sealing disk 14 of cork or other suitable material. Means is provided for holding this sealing disk in place. To this end, associated with shell 10 is a plurality of members for engaging the bottom face of the sealing disk, and in structures embodying the invention to the best advantage, these members are provided by punching out a plurality of tongues from the metal of the 65 cap, as, for example, from the skirt. Although capable of various constructions, in the form shown the inner corrugations 12 of the skirt 11 are given a plurality (in this instance 3) of inverted V-shaped cuts and the metal thus punched out is forced in to form inwardly and upwardly extending free tongues 15. As appears in the drawing, the tips of these tongues engage the bottom 70 face of the flat sealing disk 14. These bearing points are a sufficient distance from the periphery of the disk to provide positive stops at a plurality of points, thus effectively preventing the sealing disk from dropping out of the shell. In this manner the 75 disk is retained in place as long as retention is necessary, that is, until the cap is secured to a bottle. In the capping operation, as a bottle-neck enters the shell, it forces the tongues 15 back into their original position 80 in the plane of the skirt, as shown in Fig. 3. As a result of this construction, the disk-retaining members do not interfere with the proper sealing of the bottle, and at the same 85 time the crown does not have a multilated appearance after the bottle is capped.

It is noted that this method of holding the sealing disk in place is available with the ordinary style of crown, and it is not necessary to change the tools, machines and the like to provide a different type of crown in order to attain the end in view. Consequently, not only is the disk-retaining means described universally effective, but at the same time, it is extremely economical.

100 What is claimed is:

1. In a closure for bottles and the like, a metal shell having a corrugated skirt, a sealing disk, a plurality of tongues formed by punching in the metal of said shell for en- 105

gaging the face of said sealing disk in a plurality of points, said tongues being replaceable in their original position by the bottle during the capping operation.

- 5 2. A closure for bottles and the like comprising a shell having associated therewith a skirt constructed to be bent or forced inwardly against a shoulder on the mouth of a bottle to lock it thereon, and a sealing disk

located within the shell, the skirt of the shell 10 having associated therewith a plurality of members arranged to normally engage the under face of the disk and to be bent back when the skirt is in locking engagement with the bottle.

15

In testimony whereof, I have hereunto set my hand.

GEO. M. KELLER.
